[57] **CLAIM**

The ornamental design for a seat, as shown and described.

DESCRIPTION

FIG. 1 is a front elevational view of a seat showing my new design;

FIG. 2 is a front elevational view thereof;

FIG. 3 is a left side elevational view thereof, the right side being a mirror image thereof; and,

FIG. 4 is a top plan view thereof.

The rear and bottom of the seat are plain and unornamented. The broken line illustration of legs is for illustrative purposes only and forms no part of the claimed design.
